TOBACCO PIPE CLEANING DEVICE

George T. Thomas, Denville, N. J.

Application March 7, 1946, Serial No. 652,675

5 Claims. (Cl. 131—243)

1

This invention relates to apparatus for cleaning tobacco pipes.

The principal object of the invention is to provide a simple device adaptable to the cleaning of pipe orifices, including both bowls and stems, through the simultaneous action of mechanical scrubbing and of solvent for the accumulated tobacco products.

Another object is to provide such a device adapted for use with practically all common tobacco pipes regardless of differences in size and shape.

A further object is to provide such a device with which a variety of brushes or other scrubbing elements may be used, to suit varying conditions.

A still further object is to provide a device in the nature of a syringe having a brush holding shaft reciprocating through its fluid outlet, the fluid passing through an annular space around the shaft having such size that the fluid will not normally run out under the influence of gravity.

The apparatus of the invention comprises essentially a syringe which serves to pump a cleaning solution into and out of the fouled pipe orifice and of a brush, pipe-cleaner or other suitable scrubbing means so associated with the syringe that it is reciprocated in the orifice being cleaned when the syringe is operated to effect the pumping action.

The syringe, which may be of various types, is equipped with an end portion, surrounding its fluid outlet, which is so formed as to make fluid tight contact with pipe bowls or stems having a wide range of sizes and a variety of configurations. This end portion is of elastic material such as rubber formed as hereinafter described.

The invention will best be understood from a consideration of the present preferred embodiments thereof, hereinafter described as illustrative of the invention, taken in conjunction with the drawings in which:

Fig. 1 is a central section through one form of the device, in operative position on a pipe;

Fig. 2 is a similar view of another form of the device;

Fig. 3 shows the device of Fig. 1 in position on a pipe for cleaning the stem;

Fig. 4 is a section on the line 4—4 of Fig. 3;

Fig. 5 is a view through a portion of the syringe and pipe stem taken at right angles to the view of Fig. 3; and

Fig. 6 is a detail, partly in section, showing the connection between the shaft of the syringe and the shaft of the brush or other scrubbing device.

Referring to Fig. 1, it shows a pipe having a bowl 10 and a stem 11 through which is the usual bore 12 which conducts the smoke from the bottom of the bowl. The syringe here shown is in the form of a flexible and resilient bulb 14 generally oval in cross-section and having a thickened end wall 15 to increase the rigidity of this part of the bulb. Centrally disposed in this thickened portion, the bulb is provided with a fluid outlet 16 lined with a flanged cylindrical bushing 17 held in place by the resiliency of the bulb wall. Extending through the aperture in the bushing 17 is a shaft 18 which extends into a second flanged bushing 19 similarly secured in the opposite wall 15 of the bulb. The shaft 18 may be permanently secured in the bushing 19 in any suitable manner such as soldering. Surrounding the shaft 18 and extending between the bushings 17 and 19 is a compression spring 20 which augments the normal tendency of the bulb 14 to return to the shape shown after it has been deformed during its operation as a syringe. The lower end of the shaft 18 is drilled and tapped, as shown in Fig. 6, to receive the threaded end of shaft 22 of a flat circular brush 24.

The shaft 18 fits loosely in the bushing 17 so that there is an annular space between these two members for the passage of fluid. Preferably, this space is made small enough so that fluid in the bulb 14 will not run out when subjected only to the force of gravity. Subject to this condition, the space is made as large as possible. Due to the annular form of the space it has a substantial cross-sectional area so as to provide an adequate flow of liquid for cleaning purposes when the syringe is actuated to provide a pumping action. This action is produced by grasping the bulb near its thickened end 15 between the fingers and placing the thumb on the upper bushing 19 which is then pushed toward the pipe, deforming the bulb 14 and compressing the spring 20. This action drives the brush 24 downwardly in the pipe bowl 10 and forces liquid out through the space surrounding the shaft 18. When the pressure is released the resiliency of the bulb and of the spring 20, acting together, draws the brush upwardly in the pipe bowl, at the same time withdrawing any fluid which is in contact with the outlet in the syringe. During this operation the pipe is so held that its stem is in an upright position so that fluid does not run out through the bore 12. By repeating this action for a number of strokes the interior of the bowl will be thoroughly brushed and at the same time flushed out with cleaning solution.

It will be understood that prior to use the bulb 14 will be filled with the desired quantity of solution by immersing its outlet end in a supply of solution and manipulating the syringe to suck in the solution in the usual way.

Referring particularly to Figs. 3, 4 and 5, the outlet end of the bulb is provided with a mouth portion generally indicated in Figs. 3 and 4 at 26. This portion is generally oval in cross-section as shown in Fig. 4 and terminates in an inwardly-extending lip 27 so that it will closely grasp the end of a pipe stem. When used for cleaning a pipe stem the brush 24 is unscrewed from the shaft 18, and a long thin brush or scrubbing member 28, having the general shape of a common pipe-cleaner, is attached in place of the brush 24. When cleaning the stem the bulb is actuated in the same manner as when cleaning the bowl and the pipe is preferably held with the bowl in an upright position and at a higher point than the end to which the cleaning device is attached, so that no fluid runs out of the pipe. The shaft 18 is, of course, small enough to enter the bore 12 in the pipe stem.

It will be understood that in this device the spring 20 may be omitted, as shown in Fig. 5, and reliance placed entirely on the resiliency of the bulb 14, in which case the walls of the bulb will preferably be made thick enough to provide the necessary force to withdraw the scrubbing device after the bulb has been compressed.

Referring to Fig. 2, another form of the device is shown in which the syringe is of the type comprising a cylinder 30 of metal tubing or the like, having a reciprocating piston 31 mounted on a shaft 32 intermediate its ends as by horseshoe clips 33 or other securing devices inserted in grooves or otherwise attached to the shaft 32. Finger rings 35 are provided for holding the cylinder and the piston is actuated by a ring 36 into which the thumb may be inserted. This apparatus makes possible a positive force applied by the user in either direction. The withdrawing action may be aided by a spring 38 if desired, which bears at one end on the cap 39 on the cylinder and at the other end on a washer 40. The discharge end of the cylinder 30 is inserted in a fluid-sealing device 41 which may be made of rubber or similar resilient material and which has a cylindrical aperture 42 closely fitting the cylinder 30, a flared face 44 to contact the inside edge of a pipe bowl and a mouth section 45 similar to the portion 26 of the bulb 14 in the embodiment of Fig. 1. The operation of this device is similar to that of the form first described, fluid being drawn into the lower portion of the cylinder 30 below the piston 31. The aperture 46 in the member 41 is large enough to provide an annular space around the shaft 32 for the passage of fluid. The opening in cap 39 through which shaft 32 passes may be large enough to permit passage of air or holes 48 may be provided in the cap.

It is to be understood that the foregoing embodiments described in detail are merely illustrative of the invention which is to be construed broadly within the purview of the claims.

What is claimed is:

1. A tobacco pipe cleaning device comprising, a syringe having a fluid chamber and a fluid outlet communicating with said chamber, resilient means surrounding said outlet for making a fluid

tight contact between said syringe and a pipe part surrounding a pipe orifice to be cleaned, a shaft carried by said syringe and passing through said outlet and adapted to reciprocate upon actuation of the syringe, and scrubbing means carried by said shaft and adapted to extend into and scrub the walls of said pipe orifice when said shaft is reciprocated.

2. A tobacco pipe cleaning device comprising, 10 a syringe having a fluid chamber and a fluid outlet communicating with said chamber, resilient means surrounding said outlet for making a fluid tight contact between said syringe and a pipe part surrounding a pipe orifice to be cleaned, a shaft carried by said syringe and passing through said outlet and adapted to reciprocate upon actuation of the syringe, and scrubbing means carried by said shaft and adapted to extend into and scrub the walls of said pipe orifice when said shaft is reciprocated, the space between said fluid outlet and said shaft being sufficient to permit fluid to pass when the syringe is actuated but small enough to effectively prevent fluid from running out by gravity alone.

25 3. A tobacco pipe cleaning device comprising a syringe having a cylinder, a piston fitting the bore thereof, and a fluid outlet, means surrounding said outlet for making a fluid tight contact with a pipe part surrounding a pipe orifice to be cleaned, a shaft extending through said outlet and adapted to reciprocate with said piston, and scrubbing means carried by the end of said shaft adapted to scrub the walls of said orifice when said piston is reciprocated.

30 4. A tobacco pipe cleaning device comprising a resilient hollow bulb having a fluid outlet, the portion of said bulb surrounding said outlet having a configuration adapted to make a fluid tight contact with a pipe part surrounding a pipe orifice to be cleaned, a shaft extending through said outlet and said bulb to the opposite wall thereof, means securing said shaft to said opposite wall, and scrubbing means secured to that end of said shaft which extends through said outlet adapted to scrub the walls of said orifice when said shaft is reciprocated.

35 5. A tobacco pipe cleaning device comprising a resilient hollow bulb having a fluid outlet, means on said bulb surrounding said outlet for making a fluid tight contact with a pipe part surrounding a pipe orifice to be cleaned, a shaft extending through said outlet and said bulb and attached to the wall thereof opposite said outlet, a spring within said bulb normally urging said shaft toward said opposite wall, and scrubbing means for said orifice secured to the end of said shaft and adapted to reciprocate in said pipe orifice.
